UNITED STATES PATENT OFFICE.

SAMUEL JOHANNES OSCAR ASMUSSSEN, OF ILFORD, ENGLAND.

ROTARY PRINTING-MACHINE.

1,018,151.

Specification of Letters Patent.

Patented Feb. 20, 1912.

Application filed June 30, 1910. Serial No. 569,751.

To all whom it may concern:

Be it known that I, SAMUEL JOHANNES OSCAR ASMUSSSEN, a citizen of the United States of America, and a resident of No. 46 5 The Drive, Ilford, Essex county, England, have invented new and useful Improvements in and Relating to Rotary Printing-Machines, of which the following is a specification.

10 This invention relates to rotary printing machines and has for its object an improved rotary printing machine which can be utilized either for the double sided printing of a strip or sheet or for the single sided printing of two strips or sheets.

15 Rotary printing machines are known for first and second printing, in which the paper to be printed is fed to the cylinders in an endless strip or in separate sheets. In 20 both cases their printing devices consisting of printing and plate cylinders and coloring arrangements are always connected together positively in such a manner that the printing in the colors provided can be effected 25 on both sides. Hitherto however, it has not been possible to utilize both the printing apparatus totally independent of each other, each as a rotary printing machine for one-side printing in the given colors. The present 30 invention renders this possible and consists in an improved rotary printing machine with two printing apparatus for printing on one side in one or more colors, in which machine the printing apparatus can 35 be connected positively to each other for printing on both sides, or can operate independently of each other for the production of a single side print each.

40 In the accompanying drawings, which illustrate by way of example two methods of carrying out the invention, Figures 1 and 3 are elevations each illustrating diagrammatically a machine containing two printing apparatus connected positively to each 45 other. Figs. 2 and 4 are similar views, in which, however, the two printing apparatus are in the position of independent operation. Fig. 5 is a plan view showing in detail the manner of changing the arrangement of the 50 printing apparatus shown in Fig. 1 to that of Fig. 2. Fig. 6 illustrates in detail the manner of changing the arrangement of the printing apparatus shown in Fig. 3 to that of Fig. 4.

55 The machines shown in the drawings are adapted for single color printing on both

sides, that is have two single-color printing apparatus.

d_1 and d_2 are the impression cylinders, p_1 and p_2 the plate or imposing cylinders and f_1 and f_2 the coloring devices.

The improvements according to the invention can be effected in various ways. One type is shown in Figs. 1 and 2. The frames are not cast in one piece, nor, if consisting of several parts, rigidly joined together, but each printing apparatus has its own frame parts and these are jointed to a common base frame in such a manner that one apparatus can be brought into or out of contact with the other. Fig. 1 shows the first instance, Fig. 2 the last. In the other type shown in Figs. 3 and 4, two intermediate cylinders z_1 and z_2 are arranged between the impression cylinders d_1 and d_2 . If both the printing apparatus connected together are to be used for printing on both sides then these cylinders must not only be in contact with their corresponding impression cylinders, but also with each other, as shown in Fig. 3. The paper printed in the first printing apparatus is then fed with the aid of the intermediate cylinders z_1 and z_2 , to the second printing apparatus and printed on the other side therein. If the connection of the cylinders z_1 and z_2 is disconnected, as Fig. 4 shows, then each of the two printing apparatus can be operated without the slightest effect on each other.

Another feature of the invention is that each of the printing apparatus for single side printing is equipped with a feeding device for strips r_1 and r_2 , or for sheets b_1 and b_2 , a delivering apparatus a_1 and a_2 and lastly a driving device m_1 and m_2 . If then the printing apparatus are connected together, as in Figs. 1 and 3, the paper coming from r_1 or b_1 will be printed on both sides between p_1 and d_1 and p_2 and d_2 and then delivered by the delivering device a_2 . The machine delivers paper printed on both sides. If the printing apparatus are, however, disconnected as in Figs. 2 and 4, the paper coming from b_1 or r_1 is printed on one side by printing apparatus 1 and delivered by a_1 , and that coming from b_2 and r_2 printed in printing apparatus 2 and delivered by a_2 . Both the printing apparatus then operate as single machines and deliver paper printed on one side in double the quantity of that printed on both sides. Both printing apparatus with feeding and

distributing apparatus can be in operation simultaneously with the same or different speeds or one of them may also be out of operation.

5 Fig. 5 illustrates the manner in which one of the printing apparatus shown in Fig. 1 may be adjusted on the base plate so as to be moved into or out of connection with the other apparatus of the set.

10 The auxiliary base plates *g*, to which both the side frames *e* of the machine halves to be moved are screwed, and the common base plate *v* have each an eye *l* and *n* respectively. In the former a threaded spindle *k* is journaled so as to be capable of rotation only, while the eye *n* contains the nut or female thread for the spindle *k*. The threaded spindle *k* can be turned in both directions by means of bevel wheels *i* 15 and a countershaft rotatably journaled in the frame *g* having a crank *h*, and one printing apparatus thus brought closer to or moved away from the other.

20 Fig. 6, illustrates the manner in which the moving of the intermediate cylinders *z*₁ and *z*₂ may be effected to bring the two printing apparatus of Figs. 3 and 4 into or out of connection with each other. The axles of the cylinders *z*₁ and *z*₂ are both as shown 25 in the case of the cylinders *z*₁, journaled in eccentric boxes *o* the flanges *r* (see Fig. 6) of which are formed as spur gear wheels meshing with spur pinions *u* mounted on a spindle *s*. On turning this spindle by 30 means of the hand wheel *t* the eccentric boxes *c* are rotated simultaneously on both sides and the cylinders *z*₁ and *z*₂ thus brought either into the position in Fig. 3 or that in Fig. 4. At *q* a locking device is arranged for the boxes *o* to secure these in the 35 adjusted position.

40 What I do claim as my invention, and desire to secure by Letters Patent of the United States, is:—

45 1. In a rotary printing machine, the combination of two complete printing apparatus, each comprising an impression cylinder, a plate cylinder, inking rollers, and feed, delivery and driving devices, with 50 sheet reversing and transferring means between said two printing apparatus, and means for connecting and disconnecting said apparatus, whereby sheets or a web will be passed successively through said apparatus 55 and printed upon both sides when the apparatus are connected together, or will be

passed through the apparatus independently and be printed upon one side only when the apparatus are disconnected from each other.

60 2. In a rotary printing machine, the combination of two complete printing presses, each comprising an impression cylinder, a plate cylinder, inking rollers, and feed, delivery and driving devices, each of said printing presses being adapted to operate independently to cause them to print at the same time each upon one side of sheets or a web, with means for connecting the impression cylinders of said presses to cause them 65 to print successively upon opposite sides of sheets or a web.

3. In a rotary printing machine the combination of two complete printing apparatus comprising each an impression cylinder, 75 a plate cylinder, coloring rollers and feed-delivery and driving devices with two intermediate cylinders arranged between the two impression cylinders and means for connecting to each other the two impression cylinders 80 by adjustment of the two intermediate cylinders essentially as and for the purpose described.

4. In a rotary printing machine the combination of two complete printing apparatus comprising each an impression cylinder, 85 a plate cylinder, coloring rollers and feed-delivery and driving devices with intermediate cylinders arranged between the impression cylinders and journaled in eccentric boxes and means for adjusting the eccentric journal boxes of the intermediate cylinders 90 essentially as and for the purpose described.

5. In a rotary printing machine the combination of two complete printing apparatus comprising each an impression cylinder, a plate cylinder, coloring rollers and feed-delivery and driving devices with intermediate cylinders journaled in eccentric boxes 95 means for adjusting the said journal boxes and means for locking the journal boxes in the adjusted position essentially as and for the purpose described.

100 In testimony whereof I have hereunto set my hand in presence of two subscribing witnesses.

SAMUEL JOHANNES OSCAR ASMUSSEN.
